UNITED STATES PATENT OFFICE

HAROLD W. SHONNARD, OF MONTCLAIR, NEW JERSEY, ASSIGNOR TO ELEVATOR SUPPLIES COMPANY, INC., A CORPORATION OF NEW JERSEY

AUTOMATIC DOOR CLOSER

Application filed November 2, 1925. Serial No. 66,206.

The present invention relates to a novel form of door opener, preferably combined with a check to prevent slamming of the door on opening or closing or both. The 5 invention is particularly useful in connection with the sliding doors used at elevator landings, and will be hereinafter described as used in that connection, although it is to be understood that the invention is not limited 10 to elevator installations.

In order that a door closing spring of reasonable rigidity and length may be conveniently utilized for the heavy work involved in moving large sliding doors, without exceeding its elastic limit, it is desirable 15 to cause such a spring to act through a gear train affording speed reduction with consequent increase of effective effort. At the same time, in many locations, and particularly 20 in elevator installations of the kind referred to above, there is very little space available for the accommodation of apparatus for closing and checking the doors in a manner consistent with simplicity of design and economy of labor in installation.

The present invention provides means whereby the necessary increase of effort is imparted to the activating spring in a practical manner entirely consistent with the 30 space restriction above mentioned, and at the same time makes it possible to assemble the principal elements of the door closer at the factory, so as to limit the chances of mistakes and expensive delays in putting up the apparatus in an elevator shaft or other location.

The invention is illustrated in a preferred form in the accompanying drawings, wherein Figure 1 is a view in elevation of the invention 40 as applied to a sliding door on an elevator, Figure 2 is a similar but partial view of the same, showing the position of the parts with the door open, Figure 3 is a top plan view of the door closer by itself, Figure 4 is a sectional view of the same taken upon the line 4-4 in Figure 1, and Figure 5 is a horizontal sectional view taken on the line 5-5 in Figure 4.

The sliding door 10 is suspended from a 50 support 11 carried by hangers 12 which roll

in a well known manner along the guide rail 13. The attachment of the door 10 to the support 11 comprises a pivotal connection 14, and a catch 15, so that, when formed desirable, the door may be swung out of its normal plane of movement to free the door opening. 55

The opening of the door is (in the form shown) accomplished manually by means of two toggle-arms 16 and 17, pivotally joined at 18. The extremity of the arm 17 is pivotally supported by a bracket 19, while the arm 16 is pivoted between its ends upon a pin 20, fixed to the door 10. The specific mode of attachment of the arm 16 to the door 10 is one adapted to disconnection of said arm from the door at will, as described and claimed in my Patent No. 1,684,893, Sept. 18, 1928, and this forms no part of the present invention. 60 65

The door closer, preferably combined with a door check, is preferably bolted at or near the extremity of the guide rail 13, above the bracket 19, as shown in Figures 1 and 2. This arrangement is preferred, as it makes it possible to assemble the guide rail and door closer once for all at the factory. It will be 70 within the invention, however, to fix the door closer to the wall that carries the rail 13. 75

The immediate operation of the toggle arms is preferably accomplished by means of a bar 21, pivotally attached at its lower end 80 to a downward extension 22 at one end of the toggle-arm 17, and at its upper end to the end of the swinging operating arm 23 of the door closer.

The arrangement and mode of operation of this operating arm 23 are clearly shown in Figures 3, 4 and 5.

Within a suitable casing 24, a spiral operating spring 25 is arranged so as to tend to turn the vertical shaft 26 in one direction, serving to push the door 10 toward the left, or in the closed position, in Figure 1. 85

Fixed upon the top of the shaft 26 is a geared sector 27. The operating arm 23 is mounted rotatably upon a stub shaft 28 on one side of the casing 24, and is also provided with a geared sector 29. The sector 27 turns in a horizontal plane and the sector 29 in a vertical plane. 90

Between these sectors, and set at an angle 95

of forty-five degrees to the horizon, there is mounted in the casing 24 a revoluble shaft 30 carrying fixed thereon the mitered gear 31, which meshes with both sectors 27 and 29, and serves to communicate motion from the 5 spring 25 to the arm 23 for closing the door.

By adopting this combination of gears, the 10 spring may be given an increased effective ratio of effort of two or three to one—or any convenient ratio may be adopted. At the same time, the whole door closer occupies no more space than it would were the spring mounted upon a horizontal shaft applied directly to the supporting pivot of the toggle-arm 17, without any increase of effective effort.

At the same time, the arrangement described makes it possible to combine with the door closer a simple form of liquid check for preventing slamming in opening or closing or both.

For this purpose the lower end of the shaft 26 is furnished with a pinion 32 meshing with a rack 33 on the side of a plunger 34. This plunger is provided with an axial passage 35, having automatic ball valves 36 and it is moved back and forth within a cylinder 37 by the pinion 32 in a well known manner.

The checking operation is produced in a manner well known by a body of liquid driven by the plunger 34 through vents 38 at the two ends of the cylinder 37, which vents are controlled by needle-valves 39, for adjusting the degree of retardation to check slamming.

In opening the door 10, the left hand end of the toggle-arm 16 is pushed down and the parts are brought into the position shown in Figure 2. This winds up the spring 25. Upon releasing the arm 16, the spring 25 acts through the gears 27, 31 and 29, the arm 23, bar 21 and extension 22 to swing the toggle arm 17 anti-clockwise in Figure 2, thereby straightening the toggle joint and closing the door as shown in Figure 1.

The motive force for revolving the shaft 26 of the door closer need not necessarily be a spring, as my broad invention covers any motive force employed for this purpose; and in general a variety of changes may be made in this construction without departing from the invention, which is not limited to the details herein shown and described.

What I claim is—

1. An automatic closing device for sliding doors comprising a vertical shaft provided with a toothed sector, an operating arm having a toothed sector adapted to swing in a vertical plane, an intermediate beveled gear meshing with said two toothed sectors and motive means for said vertical shaft.
2. In combination with a door and toggle arms adapted to move the same back and forth in its own plane; a spring-operated door closer having an operating arm rota-

table in a vertical plane operatively connected with said toggle arms, a vertical shaft adapted to be turned by said spring, and speed reducing gearing between said vertical shaft and operating arm.

3. In combination, a sliding elevator shaft door, a supporting rail on which said door slides, toggle arms for operating said door, a spring operated door closer, said closer having an operating arm rotatable in a vertical plane operatively connected with said toggle arms and also having a vertical shaft adapted to be turned by said spring and speed reducing gearing between said vertical shaft and operating arm; said door closer being mounted above the door outside of said rail, said door being arranged to slide beneath the door closer.

4. In combination, a sliding elevator shaft door and an automatic closing device for said door comprising a vertical shaft, a spring for rotating the same, a horizontal shaft operatively connected with said vertical shaft, and means operatively connected with said horizontal shaft for moving said sliding door.

5. In combination a sliding door, toggle-arms connected to said door and to a fixed part, said toggles swinging in a plane alongside said door, a link connected at one end to one of said toggle arms, a pivoted arm connected to the other end of said link, said arm swinging in a plane parallel to the plane in which said toggle-levers swing, a vertical spindle, speed reducing gearing connecting said spindle and arm, including a gear-segment of said arm, and a spiral spring around said spindle, adapted to be tensioned by and react upon said spindle, to oppose and assist the opening and closing of said door.

6. A combination according to claim 5, further including a checking means, comprising a piston and a gear connection between said spindle and piston.

7. Sliding-shaft-door operating means, comprising a casing, a spindle, a spiral spring around said spindle, said spring being attached to said spindle and to said casing, checking means comprising a pinion on said spindle, a piston moving tangentially to said pinion, teeth on said piston meshing with said pinion, and means for transmitting the force of said spring to a door, comprising a toothed segment pivoted on an axis normal to said spindle, a second pinion on said spindle, and an intermediate gear connecting said toothed segment and said last-named spindle.

In testimony whereof I hereto affix my signature on this 26th day of October, 1925.

HAROLD W. SHONNARD.
